UNITED STATES PATENT OFFICE.

CARL G. THOMPSON, OF ST. LOUIS, MISSOURI.

PUSHER AIRPLANE.

Application filed March 17, 1928. Serial No. 262,410.

My invention relates to pusher airplanes, and it is a distinct and practical improvement in the construction thereof to overcome certain practical objections to, and defects in, the present types of airplanes.

The objects of my present invention are first, to provide an airplane so constructed as to afford maximum penetration of the air, both in taking off and in flight; second, affording maximum of lift; third, affording maximum stability, such as inherent, static, dynamic, longitudinal, directional and lateral; fourth, affording the maximum of safety in landing; fifth, the provision of airfoils affording the maximum useful dynamic reaction; sixth, the provision of superposed sweep back airfoils, each of which is of less dimension laterally than longitudinally and which have a convexed dipping trailing edge, dipping side edges which gradually disappear toward a convexed leading edge which is the termination of an upwardly curved breast section of each airfoil; seventh, the provision of an auxiliary, or intermediate rear airfoil having a dipping rear edge and dipping side edges; eighth, positioning of rudders in advance of the airfoils; ninth, positioning of superposed elevators between the breast portions of the superposed airfoils; tenth, the provision of movable opposed, vertically disposed booster planes in advance of the auxiliary airfoil; eleventh, the positioning of the power plant upon the lower airfoil; twelfth, the provision of a pusher propeller; thirteenth, the provision of a horizontally disposed landing propeller located below the trailing end portion of the lower airfoil; and, fourteenth, the provision of a wheel landing gear.

A further object of the invention is the provision of a pusher airplane, which possesses advantages in points of simplicity and efficiency, and, at the same time proves itself comparatively inexpensive in cost of manufacture.

With the above and other objects in view, the invention consists in the novel features of construction, arrangement and combination of parts hereinafter more fully described and finally pointed out in the claims hereto appended.

Referring to the accompanying drawings forming a part of this specification, wherein like characters of reference denote similar parts throughout the several views:

Fig. 1, is a side elevation of a pusher airplane embodying the features of my invention.

Fig. 2, is a transverse vertical sectional view of the airplane.

Fig. 3, is a trailing end elevation of the airplane.

Fig. 4, is a longitudinal vertical sectional elevation of the airplane.

Fig. 5, is a top plan view thereof.

Fig. 6, is a detail of one of the landing wheels and its connection with the lower airfoil.

In carrying out the aim of my present invention, I employ a lower airfoil 1 having a flat diverging body portion 2 terminating at opposite ends in reversely curved portions, so as to provide a rear dipping edge portion 3, which is given a convex cambered trailing edge 4, and to provide an upwardly gently curved forward breast portion 5 for the airfoil. The flat diverging body portion 2 and the upwardly curved breast portion 5 thereof are provided with the sweep back dipping side edge portions 6 having the sweep back edges 7 which merge at their rear ends with the rear dipping edge portion 3 and the trailing edge 4, respectively, and which side dipping edge portions 6 practically fade out at the leading edge 8 of the airfoil 1 which is given a conveyed camber or curvature, as will be apparent in Fig. 5. In plan view, the lower airfoil 1, as will be apparent from Fig. 1, has a narrow leading edge which sweeps back to a trailing edge. The lower airfoil 1 is mounted upon and suitably secured to a pair of suitably connected diverging longérons designated 9, the forward ends 10 of which are curved upwardly and forwardly beyond the leading edge 8 of the airfoil 1.

Spaced from and disposed above the longérons 9 are a pair of suitably connected upper diverging longérons 11, which are rigidly connected with the lower longérons 9 by means of a plurality of suitable supporting struts 12 to form the frame work of an open fuselage. The upper longérons 11 extend beyond the rear ends of the lower longérons 9 and have their rear ends curved downwardly, as at 13, and their forward ends curved upwardly, as at 14. The leading ends of the upwardly curved portions 14 of the upper longérons 11 are disposed above and to the rear of the leading ends of the upwardly curved portions 10 of the lower longérons 9 and they

are connected to each other by means of suitable connecting straps 15.

Mounted upon and securely fixed to the upper longérons 11 is an upper airfoil 16 having a flat diverging body portion 17 terminating at opposite ends in reversely curved portions, so as to provide a rear dipping edge portion 18, which is given a convex cambered trailing edge 19, and to provide an upwardly 10 gently curved breast portion 20 for the upper airfoil 16. The flat diverging body portion 17 and the upwardly curved breast portion 20 thereof are provided with the sweep back dipping side edge portions 21 having the sweep 15 back edges 22 which merge at their rear ends with the rear dipping edge portion 18 and the trailing edge 19, respectively, and which side dipping edge portions 21 practically fade away at the leading edge 23 of the airfoil 16, 20 which is given a convexed camber or curvature, as will be apparent from Fig. 5. Briefly, both the lower airfoil 1 and the upper airfoil, or planes 16 are reversely curved longitudinally, and transversely curved and resemble 25 very much a shoe horn, in plan view, and inverted pans in transverse sectional elevation, as will be apparent from Figs. 5 and 2, respectively. As clearly shown in Figs. 2 and 4, the upper airfoil 16 has its rear dipping 30 edge 18 and side dipping edges 21 extending beyond the rear dipping edge 4 and side dipping edges 7 of the lower airfoil 1 and has its leading edge 23 disposed shortly to the rear of the leading edge 8 of the lower airfoil 35 1. In short, the upper airfoil 16 is of greater area than the lower airfoil and extends over the rear and side edges of the lower airfoil 1.

From the foregoing, it will be apparent that airfoils, as described, will cause the displacement of air just as a goose, or as the prow of a boat displaces both air and water, thus creating an upward rising current of air around the dipping side edges 7 of the lower airfoil 1 for displacing the vacuum adjacent the 40 upper surface of the lower airfoil 1, incidentally densifying the air between the under-surface of the upper airfoil 16 and the upper surface of the lower airfoil 1 to establish maximum stability to the superposed foils 1 and 16. As the aircraft advances in flight, the 45 densified air is further compressed by the enlarged area of the rear dipping edge portions 6 of the lower airfoil 1. A similar dynamic pressure is created by the upper airfoil 16 due to the impact of the air stream flowing between the upper and lower airfoils 1 and 16.

A narrow auxiliary airfoil 24 having a flat portion 25 is disposed between the upper and 50 lower airfoils 1 and 16 at the rear end portion of the aircraft and is mounted upon suitable rearward and downwardly curved longérons 26 which are supported by the rearmost supporting struts 12 and braced by the bracing rods 27 which also brace the rear ends of the

upper longérons 11. This auxiliary airfoil 24 has dipping side edge portions 28 with the lower edge 29, the dipping rear portion 30 and the trailing edge 31. The auxiliary airfoil 24 adds further to the lifting of the 70 rear end of the aircraft due to the impact thereof with the air stream between the upper, and lower airfoils 1 and 16 and also adds to the general stability thereof.

To further increase the dynamic pressure, 75 I employ what I term booster wings which are in the form of two vertically disposed planes 32. These booster wings are hingedly connected along their rear edges to certain of the rearmost supporting struts 12 and are 80 adapted to be swung outwardly at any angle desired between the upper and lower airfoils 1 and 16 in advance of the rear ends of the dipping side edge portions thereof, and their adjusted positions are made secure by means 85 of the slotted arms 33 which coact with the guide members 34 which pass through the slotted arms. The arms are locked to the guide members 34 by suitable fastening devices 35.

The leading or prow end of the aircraft is provided with a vertically disposed steering vane or rudder shaft 36 supported by means of bearing members 37 and 38 and by which shaft the rudders 39 and 40 are carried and controlled by a lever 41 through the connection 42.

Disposed between the forward and upwardly curved breast portions of the lower and upper airfoils 1 16 are two pairs of 100 superposed elevators 43 and 44. Each pair of elevators are supported by the shafts 45 and 46 mounted in the bearings 47 and 48, which are secured by the forwardmost supporting struts 12. Each pair of elevators 43 105 and 44 are connected by means of connecting links 49 which are pivotally connected at their ends to the elevators. Shaft 45 is provided with a cross arm 50 and both pairs of elevators are controlled in unison by means of a lever 51 through the medium of two pairs of spaced parallel arranged connections 52.

The aircraft is supported upon the ground by means of three landing wheels 53, 54 and 55. Wheels 53 and 54 are the rear wheels, 115 and wheel 55 is the forward wheel. The wheels are each supported by means of a suitable supporting member 56 associated with a shock absorbing device 57, which includes a cylindrical member 58 secured to the lower 120 airfoil 1 and provided with a coiled spring 59 encircling the shank portion 60 of each supporting member 56 and which passes upwardly through the cylindrical member 58.

A stabilizer 61 is secured to, and depends 125 from the lower airfoil 1 and it is disposed longitudinally thereof with its lower edge extending below the rear and side dipping edges 4 and 7 of the lower airfoil 1. The lower forward edge of the stabilizer 61 is 130

curved upwardly, as at 62, and the leading edge 63 of the stabilizer 61 stops short of the leading edge 8 of the lower airfoil 1.

The aircraft is driven or pushed by means 5 of a propeller 64 driven by means of a suitable motor 65 mounted upon the lower airfoil 1 through the medium of the shaft 66, including a suitable transmission 67 controlled by means of a foot pedal 68.

10 For the purpose of assisting in the landing of the aircraft, I employ a horizontally disposed lifting propeller 69 which is arranged below the rear end portion of the lower airfoil 1 within the bounds of the side and 15 rear dipping edge portions thereof. The driving of this propeller 69 is controlled by the foot pedal and transmission. When the pedal is pushed down to its forward position, it releases the propeller 64 from positive rotation and starts the propeller 69 to 20 rotating, which has a light lifting effect upon the aircraft, allowing it to land gently.

From the drawings, it will be apparent 25 that the advancing edges of the airfoils are of less width than the longitudinal axis thereof and that their side edges gradually sweep back to the trailing edges of the airfoils, thereby gradually increasing the supporting area so that the impact with the air 30 stream becomes gradually greater toward the trailing edges of the airfoils instead of at the leading edges thereof. Thus, it will be seen that the initial lift of the aircraft is due to impact of the breast portions of the airfoils and then the lift is completely established at the trailing ends of the airfoils.

The positive and negative pressure becomes 35 greater at the rear dipping edges of the airfoils due to the impact with the air stream below the lower airfoil and between the superposed airfoils, thus aiding in the lift and stability of the airfoils. This dynamic action also is increased due to the fact that the dipping side edges of the airfoils sweep back 45 from the convexed leading edges of the airfoils to a widened area at the trailing edges thereof.

From the foregoing description, it is evident 50 that a simple device for this purpose has been disclosed, but it is to be understood that I do not desire to restrict, or limit myself to the very details of the construction shown and described, which is merely illustrative, it being obvious that changes, not involving the exercise of the invention, may 55 be made without conflicting or departing from the spirit of the invention within the scope of the appended claims.

What I claim is:

60 1. In a pusher airplane, superposed airfoils, each having a breast portion terminating in a leading edge, a dipping trailing edge and dipping side edges vanishing as they approach the leading edges of the airfoils.

2. In a pusher airplane, superposed airfoils each having a breast portion terminating in a leading edge, a dipping trailing edge and dipping side edges vanishing as they approach the leading edges of the airfoils, the upper of said airfoils being of a greater area than the lower airfoil.

3. In a pusher airplane, superposed airfoils each having a breast portion terminating in a leading edge, a dipping trailing edge and dipping side edges vanishing as they approach the leading edges of the airfoils, the upper of said airfoils being of a greater area than the lower airfoil and having its leading edge disposed to the rear of the leading edge of the lower airfoil.

4. In a pusher airplane, superposed airfoils each having a breast portion terminating in a leading edge, a dipping trailing edge and dipping side edges vanishing as they approach the leading edges of the airfoils, the upper of said airfoils being of a greater area than the lower airfoil and having its leading edge disposed to the rear of the leading edge of the lower airfoil and vertically disposed movable booster wings disposed between the dipping side edges of the airfoils.

5. In a pusher airplane, superposed airfoils each having a breast portion terminating in a leading edge, a dipping trailing edge and dipping side edges vanishing as they approach the leading edges of the airfoils, the upper of said airfoils being of a greater area than the lower airfoil and having its leading edge disposed to the rear of the leading edge of the lower airfoil, vertically disposed movable booster wings disposed between the dipping side edges of the airfoils and a stabilizer depending from the lower airfoil and disposed longitudinally thereof.

6. In a pusher airplane, superposed airfoils each having a breast portion terminating in a leading edge, a dipping trailing edge and dipping side edges vanishing as they approach the leading edges of the airfoils, the upper of said airfoils being of a greater area than the lower airfoil and having its leading edge disposed to the rear of the leading edge of the lower airfoil, vertically disposed movable booster wings disposed between the dipping side edges of the airfoils, a stabilizer depending from the lower airfoil and disposed longitudinally thereof and a manually actuated rudder disposed in advance of the superposed airfoils.

7. In a pusher airplane, superposed airfoils each having a breast portion terminating in a leading edge, a dipping trailing edge and dipping side edges vanishing as they approach the leading edges of the airfoils, the upper of said airfoils being of a greater area than the lower airfoil and having its leading edge disposed to the rear of the leading edge of the lower airfoil, vertically disposed movable booster wings disposed between the dip-

ping side edges of the airfoils, a stabilizer depending from the lower airfoil and disposed longitudinally thereof, a manually actuated rudder disposed in advance of the superposed airfoils and manually actuated superposed elevators disposed between the breast portions of said airfoils.

8. In a pusher airplane, superposed airfoils each having a breast portion terminating in a leading edge, a dipping trailing edge and dipping side edges vanishing as they approach the leading edges of the airfoils, the upper of said airfoils being of a greater area than the lower airfoil and having its leading edge disposed to the rear of the leading edge of the lower airfoil, vertically disposed movable booster wings disposed between the dipping side edges of the airfoils, a stabilizer depending from the lower airfoil and disposed longitudinally thereof, a manually actuated rudder disposed in advance of the superposed airfoils, manually actuated superposed elevators disposed between the breast portions of said airfoils, a power plant mounted upon the lower airfoil, and a propeller disposed below the dipping trailing edge of the upper airfoil and to the rear of the trailing edge of the lower airfoil.

9. In a pusher airplane, superposed airfoils each having a breast portion terminating in a leading edge, a dipping trailing edge and dipping side edges vanishing as they approach the leading edges of the airfoils, the upper of said airfoils being of a greater area than the lower airfoil and having its leading edge disposed to the rear of the leading edge of the lower airfoil, vertically disposed movable booster wings disposed between the dipping side edges of the airfoils, a stabilizer depending from the lower airfoil and disposed longitudinally thereof, a manually actuated rudder disposed in advance of the superposed airfoils, manually actuated superposed elevators disposed between the breast portions of said airfoils, a power plant mounted upon the lower airfoil, a propeller disposed below the dipping trailing edge of the upper airfoil and to the rear of the trailing edge of the lower airfoil and a vertically disposed landing propeller disposed below the trailing end of the lower airfoil.

10. In a pusher airplane, superposed airfoils each having a breast portion terminating in a leading edge, a dipping trailing edge and dipping side edges vanishing as they approach the leading edges of the airfoils, the upper of said airfoils being of a greater area than the lower airfoil and having its leading edge disposed to the rear of the leading edge of the lower airfoil, vertically disposed movable booster wings disposed between the dipping side edges of the airfoils, a stabilizer depending from the lower airfoil and disposed longitudinally

thereof, a manually actuated rudder disposed in advance of the superposed airfoils, manually actuated superposed elevators disposed between the breast portions of said airfoils, a power plant mounted upon the lower airfoil, a propeller disposed below the dipping trailing edge of the upper airfoil and to the rear of the trailing edge of the lower airfoil, a vertically disposed landing propeller disposed below the trailing end of the lower airfoil and a three wheel landing gear upon which the lower airfoil is mounted.

11. In a pusher airplane, an upper airfoil, a lower airfoil of smaller area, an auxiliary airfoil of relatively small area, said upper and lower airfoils having curved breast portions terminating in leading edges, dipping trailing edges and sweep back dipping side edges and said auxiliary airfoil having dipping side edges terminating in a dipping trailing edge.

12. In a pusher airplane, an upper airfoil, a lower airfoil of smaller area, an auxiliary airfoil of relatively small area, said upper and lower airfoils having curved breast portions terminating in leading edges, dipping trailing edges and sweep back dipping side edges, said auxiliary airfoil having dipping side edges terminating in a dipping trailing edge and vertically disposed hingedly supported booster wings disposed between the dipping side edges of the upper and lower airfoils.

13. In a pusher airplane, upper foils and lower airfoils, said airfoils each having a narrow convexed trailing edge, upwardly curved breast portions, sweep back dipping side edges terminating in convexed dipping trailing edges whereby to form airfoils substantially cone shaped in plan view.

14. In an aircraft structure, in combination, a lower airfoil, an upper airfoil, a power plant mounted on said lower airfoil, a propeller adjacent the rear ends of the airfoils and disposed below the upper airfoil, a vertical rudder in advance of both airfoils, an elevator disposed between the upper and lower airfoils and a stabilizer depending from the lower airfoil and disposed longitudinally thereof.

15. In an aircraft structure in combination, a lower airfoil, an upper airfoil, a power plant mounted on said lower airfoil, a propeller adjacent the rear ends of the airfoils and disposed below the trailing edge of the upper airfoil and to the rear of the lower airfoil, a vertical rudder in advance of both airfoils, an elevator disposed between the upper and lower airfoils at the forward ends thereof and a stabilizer having its lower edge convexed at its forward end depending from the lower airfoil and disposed longitudinally thereof.

16. In an aircraft structure, in combination, superposed airfoils having sweep back

dipping side edges, dipping trailing edges, relatively flat center portions terminating forwardly in upwardly curved breast sections having convexed leading edges, an auxiliary airfoil, a stabilizer depending from the lower of said superposed airfoils, a vertical rudder supported in advance of said airfoils, means for actuating said rudder, superposed elevators disposed between the forward upwardly curved ends of said airfoils, means for actuating said elevators in unison, a power plant mounted upon the lower of said superposed airfoil, a propeller driven by said power plant and disposed so as to push the aircraft, a three wheel landing gear and a landing propeller disposed below the rear portion of the lower of said superposed airfoils and propelled by said power plant when the first mentioned propeller has ceased rotation under power.

17. In an aircraft structure, a top airfoil having a long sweep back chord, a short lead-

ing edge span and a longer trailing edge span than the leading edge span, a lower airfoil having a long sweep back chord, a short leading edge span and a longer trailing edge span than the leading edge span and suspended from the top airfoil, an auxiliary airfoil disposed between the top and lower airfoils at the rear ends thereof, a power plant in advance of the auxiliary airfoil and supported by the lower airfoil, a vertical rudder in advance of said top and lower airfoils, elevators disposed between the top and lower airfoils, a three wheel landing gear, a pusher propeller driven by said power plant and a horizontally disposed landing propeller below said lower airfoil driven by said power plant when the pusher propeller has ceased rotation under power.

In testimony whereof, I have hereunto affixed my signature.

CARL G. THOMPSON.
